LOCK FOR FOLDING TABLE-LEGS.

1,071,296.

Specification of Letters Patent.

Patented Aug. 26, 1913.

Application filed March 25, 1912. Serial No. 635,947.

To all whom it may concern:

Be it known that I, CARL ALFRED CARLSON, a citizen of the United States, residing at Jamestown, in the county of Chautauqua and State of New York, have invented certain new and useful Improvements in Locks for Folding Table-Legs, of which the following, taken in connection with the accompanying drawings, is a specification.

10 The invention relates to locks for tables having folding legs, and the object of the improvement is, first, to provide mechanism for rigidly locking the upper ends of the legs of a folding table when in the set-up position, yet so hinging said legs that they may be folded against the under side of the table top; second, to provide a catch on the lock to hold the leg in the folded position and also to strengthen the lock; and third, 20 to provide means in combination with said lock for taking up or adjusting the clamp of the lock upon the end of the table leg so as to hold it as rigidly as possible and allow for wear; and the invention consists in 25 the combination and arrangement of the parts as shown in this specification and the accompanying drawings and pointed out in the claims.

In the drawings, Figure 1 is a plan view 30 from the under side of one of the corners of a folding table with the leg in the set-up position; and Fig. 2 shows the adjacent corner with the leg in the folded position, the end of said leg being shown in Fig. 1. Fig. 3 is an elevation of the lock with the upper 35 end of the leg in the set-up position, the table top being shown in section. Fig. 4 is a sectional view of the table top with a side elevation of the lock and the leg in the partially 40 folded position showing the operation of the catch for holding the leg in the folded position. Fig. 5 is a perspective view of the hinge plate for the table lock. Fig. 6 is a detail perspective view of the locking 45 lever which is pivotally attached to the hinge plate shown in Fig. 5. Fig. 7 is a perspective view of the U-shaped bracket piece for the lock for the upper end of the table leg, showing the hinge pin thereacross and the spring catch attached thereto; and 50 Fig. 8 is a detail perspective view of the spring catch separated from said bracket piece.

Like numerals of reference refer to corresponding parts in the several views.

The numeral 10 designates the table top which is made with a frame 11 around the outer edges of its under side and attached to said table top in such a manner as to form corners within which the angular 60 sheet metal U-shaped bracket pieces 13 are attached.

The legs 12 are attached to the table top 10 and frame 11, being hinged within the corners of said frame by means of hinge 65 locks, each of which is composed of the bracket piece 13 which is bent in angular form to fit within said corner, and the legs 14 of the U-shaped bracket piece 13 extend beyond the side of the leg 12 when in the 70 set-up position, the opening between said legs of said bracket forming a convenient space within which the leg 12 may be folded and the extension of the legs 14 of the bracket forming convenient means for locking the leg 12 within the three-sided inclosure of the bracket piece 13.

The bracket piece 13 is attached within the corner of the frame 11 and to the top 80 10 by means of suitable screws through the holes 15 in bracket piece 13, and by means of a block 16 which abuts against the otherwise unsupported side or leg of the bracket piece 13. The block 16 serves as an attaching block for a lug 17 on the end of said 85 leg of the bracket piece 13, which lug is preferably cut from said leg 14 and bent at right angles therefrom out over the block 16 to receive a suitable screw therethrough. The block 16 also receives the end of the 90 leg 12 holding it in a horizontal position at a spaced distance from the table top 10, as shown in Fig. 3.

The leg 12 is hinged within the bracket piece 13 by means of a hinge plate 18 which 95 is attached to the side of the upper end of the leg 12 by screws and preferably fills the space between the legs of the U-shaped bracket 13, said U-shaped bracket has oppositely placed holes to receive a hinge pin 100 20 thereacross for inclosing the leg 12 within the U-shaped bracket 13 so that when in the set-up position said plate 18 forms the fourth side of the opening within the bracket piece 13, that is, the upper end of 105 the leg is held on all sides. The plate 18 has its upper end turned in a tube 19 to receive therethrough the pin 20. The upper end of the leg 12 should be fitted to the inclosure so that it exactly fills the inclosure. 110

formed by the angular sides of the plate 13 and the plate 18 and should rest squarely against the under side of the table top 10 when in the set-up position, as shown in

5 Fig. 3.

In order to lock the leg 12 firmly in its set-up position within the angular recess formed by the plate 13, a lever 21 is pivotally attached to the outer side of the hinge plate 18 by means of a suitable rivet and in such position upon the plate 18 that the notched locking end 22 of the lever 21 may be brought into locking engagement with a slot 23 in one of the legs of the plate 13. 10 The slot 23 is so placed that it firmly holds the leg 12 in the set-up position, pressing it against the under side of the table top 10 within the angular plate 13, the side 25 of said slot 23 being given a slight angle of 15 inclination which presses the end of the lever 21 against the plate 18, thereby pressing the square upper end of the leg 12 firmly into the recess within the sides of the plate 13, the end 24 of the slot 23 being made sufficiently long to permit of said inclination of the side 25. The side 25 also provides a wider opening toward the end 24 which leads the end 22 of lever 21 into the slot 23 so that if the leg 12 is not pressed firmly into 20 the bracket 13 but is approaching the set-up position, it will permit of the lever 21 being operated to press it firmly into line since the end 22 will catch within the inclined side 25 and draw the leg into place as the lever 25 moves up said inclination.

The leg is held in the set-up position with still greater rigidity by means of a notch 26 in the opposite leg of the plate 13 into which notch the lever 21 enters, a locking notch 30 being provided in the side of the lever 21 to engage in the notch 26. It is apparent that the notched end 22 and the notch 30 hold on the outer sides of the two legs of bracket 13, thereby binding the leg firmly in 35 line. A broad finger hold 27 is provided on lever 21 for pressing said lever down into place and for releasing the same, and it is obvious that the locking of the leg 12 in the set-up position and the release of said leg 50 is entirely manually operated. The length of the lever 21 with its handle or finger hold 27 is sufficient to force said lever into a strong binding engagement.

In order to hold the legs 12 in the folded 55 position as they extend around the under side of the table top adjacent the frame 11, a spring 28 is provided which has a lug 29 with a hole therethrough and extending at right angles therefrom for attaching to block 60 16 on the opposite side of said block from lug 17. A hole 31 is provided midway of the length of spring 28 to receive the end of hinge pin 20 as it extends through the adjacent side of the bracket 13, said hinge pin 65 being provided with a shoulder near each

end to space the parts and is riveted so as to hold the parts firmly in place.

The end 32 of the spring 28 projects from beneath and beyond the lug 17 and has a lengthwise crimp 33 therein which is inclined toward the outer edge so that the edge of the plate 18 presses down over the crimp 33 and holds beneath said crimp, and the crimp shuts into a small notch 34 in the side of leg 12, as shown in Fig. 4. A crosswise bend 35 is provided on spring 28 adjacent the end of the leg of bracket 13 so as to bring the end 32 of spring 28 into line with the inner side of said leg so that said end 32 will receive the edge of the plate 18 as it presses 80 against the same and snap into locking engagement with crimp 33. The block 16 presses against the spring 28, holding it firmly in line and strengthening the same, as well as stiffening and supporting the leg of 85 the bracket 13.

It is apparent that the upper end of the leg 12 will wear and become a loose fit after being refolded a great number of times, and that as soon as it so wears said leg will be 90 loose and the support of the table become insecure in proportion to the play permitted within the bracket 13. Accordingly a screw 36 is provided in the side of the upper end of leg 12 opposite plate 18, which screw is 95 preferably a machine screw with a broad head which can be quickly withdrawn slightly when the end of the leg wears, thereby tightening the fit of the upper end of said leg since the lever 21 presses the head 100 of said screw against the inner end of the bracket 13 so that the user may have a continuous tight fit for said upper end and a firm holding of the table leg.

I claim as new—

1. A locking hinge for a table leg comprising a bracket plate having a sidewise opening therein and extending around three sides of the upper end of the table leg, a hinge plate on the fourth side of the table leg pivotally attached to said bracket across the mouth of said sidewise opening, and a lever pivotally attached to said hinge plate and locking on the sides of said bracket plate across said sidewise opening to bindingly hold said upper end of the table leg.

2. A folding table comprising a table top, a frame on the underside of said top, a table leg, a bracket piece attached on the inner side of said frame on said table top, said bracket piece having an opening therein to receive the upper end of the table leg, a hinge plate attached to said leg and pivotally attached in said bracket piece, a lever pivotally attached to said hinge plate, said bracket piece having a slot opposite the end of said lever when in the set-up position to receive said end in locking engagement, said bracket piece having a notch in the side thereof opposite said slot to receive said

lever in locking engagement when in the set-up position.

3. A folding table comprising a table top, a frame on the under side of said top, a table leg, a bracket piece attached on the inner side of said frame on said table top, said bracket piece having an opening therein to receive the upper end of the table leg, a hinge plate attached to said leg and pivotally attached in said bracket piece, a lever pivotally attached on the outer side of said hinge plate, said bracket piece having a slot opposite the end of said lever when in the set up position to receive said end in locking engagement, the side of said slot formed at an angle inclined toward said hinge plate to bindingly draw the end of said lever toward said hinge plate, said bracket piece having a notch in the side opposite said slot to receive 20 said lever in close locking engagement when in the set up position.

4. A locking hinge for a table leg comprising a bracket plate having a sidewise opening therein and extending around three sides of the upper end of the table leg, a hinge plate on the fourth side of the table leg pivotally attached to the opposite sides of said bracket plate across the mouth of said sidewise opening, a lever pivotally attached to said hinge plate and locking in openings on the sides of said bracket plate across said sidewise opening, a spring plate attached to the side of said bracket plate and extending out alongside of said hinge plate 35 on the table leg, and a crimp in said spring to engage over the edge of said hinge plate and hold the table leg in the folded position.

5. A locking hinge for a table leg comprising a flat U-shaped strip to extend around three sides of the upper end of the table leg, a hinge plate for the table leg on

its fourth side pivotally attached to the legs of said U-shaped strip across its mouth and near its top edge, a lever pivotally attached to the outer side of said hinge plate and locking in openings on both legs of said U-shaped strip across said mouth, and a take-up screw in the side of the table leg opposite said lever to press against the inner side of said U-shaped strip and adjust the fit of the upper end of the table leg in said U-shaped strip, substantially as and for the purpose specified.

6. A locking hinge for a table leg comprising a metal U-shaped strip fitting closely around three sides of the upper end of the table leg and forming a holding bracket therefor, a hinge plate on the fourth side of the table leg pivotally attached to the legs of said holding bracket across its mouth, and near its upper edge, a lever pivotally attached to said hinge plate and locking in a notch and slot on the legs of said holding bracket across said mouth, a spring plate attached to said U-shaped holding bracket alongside the inner leg, said spring plate having a hold lug extending therefrom, a lug bent from the end of the adjacent leg of the U-shaped holding bracket and extending out over said spring and bracket to hold 70 said spring, a block attached to the table top adjacent said spring to receive the end of the table leg thereon and attaching screws through said lugs into said block, the end of said spring extending in the path of said 75 table leg to hold it in the folded position.

In testimony whereof I have affixed my signature in the presence of two witnesses.

CARL ALFRED CARLSON.
